UNITED STATES PATENT OFFICE.

JOHN A. GIBSON, OF TOLEDO, OHIO.

CAR DOOR.

Application filed June 23, 1919. Serial No. 306,064.

To all whom it may concern:

Be it known that I, JOHN A. GIBSON, a citizen of the United States, residing at Toledo, in the county of Lucas and State of Ohio, have invented certain new and useful Improvements in a Car Door, of which the following is a specification.

This invention relates to improvements in car door structures and has for its primary object to provide a conveniently operable mechanism capable of shifting the door laterally with relation to the door hangers and car body whereby the door may be moved clear of such objects within the car that might be engaged therewith and thereby obstruct its movement.

Another object is the provision of an adjusting mechanism of this character for doors whereby the entire door is moved bodily a uniform distance from the car body thereby facilitating its sliding adjustment upon the supporting track.

Another object is the application of such devices to the door as permits of the utilization of the adjusting means therefor to lock the door in closed position.

With these and other objects in view as will appear as the description proceeds the invention comprises the novel features of construction, combination of elements, and arrangement of parts which will be more fully described in the following specification and set forth with particularity in the claim appended hereto.

Figure 1 represents a fragmentary side elevation of a car body illustrating the improved door applied thereto, and,

Figure 2 represents a vertical sectional view through the car body illustrating the door in end elevation.

Referring to the drawing in detail, wherein similar reference numerals designate corresponding parts throughout the several views the numeral 5 indicates one of the side walls of a car body provided with the usual roof 6, floor 7 and door way 8. A grooved supporting track 9 is secured horizontally above the door way 8 and extends a distance to one side thereof and receives the pairs of rollers 10 carried by substantially T-shaped hangers 11 the depending portions of which extend below the track 9 and are bifurcated and apertured to receive supporting pins 12 on which are rotatably mounted rollers confined between the bifurcations of each hanger. Depending retaining arms 13

are secured to the head portions of the hangers 11 and are provided with angular lower terminals seated in the groove 14 formed in the bottom of the track 9 to prevent accidental displacement of the movable hangers from the track.

The horizontally slidable door 15 is arranged exteriorly of the car body 5 and is provided with supporting plates 16 carrying horizontally slotted brackets 17 which are confined between the bifurcations of the respective hangers 11 and are supported upon the rollers mounted upon the supporting pins 12. Owing to the connection of the brackets 17 with the hangers 11 the door may be moved longitudinally of the car body 5 to cover or uncover the door way 8 as desired, and owing to the mounting of the pins 12 in the slotted brackets 17 the door may be moved laterally, with relation to the car body 5 in order to clear an object contained within the car and bearing thereon in such manner as to obstruct the sliding movement of the door.

Vertically disposed rock shafts 18 are journaled in bearing members 19 to the outer and top and bottom portions of the door 15 and the opposed terminals of the respective rock shafts are provided with laterally directed crank arms 20 carrying crank pins 21. The pins at the upper terminals of the shafts are slidably and rotatably confined in the groove 14 in the underside of the track 9 whereby oscillatory movement of the shafts produces a lateral movement of the door 15 with relation to the car body owing to the confinement of the crank pins 21 in the groove 14. The crank pins 21 at the lower terminals of the rock shafts are confined, rotatably and slidably in a groove 22 formed in the guide 23 secured to the car floor 7 adjacent the door way 8. The crank arms of the opposite terminals of the shafts 18 occupy the same angular position with relation to the shafts whereby the ends of the door are maintained in uniformly spaced relation to the car body during adjustment. When the rock shafts 18 are adjusted to project the door 15 inwardly, said door is received within the opening or door way 8 thereby preventing accidental movement of the door along the track 9.

For convenience in manually rocking the shafts 18 handle arms 24 are pivotally secured at 25 and, when moved to horizontal position as suggested in full lines in Figure

- 1, provide convenient means for oscillating the shafts. When not in use, the arms may be swung downwardly as suggested by dotted lines in Figure 1.
- 5 When the door 15 is closed and moved inwardly to occupy the door way 8, the arms 24 lie in contact with the portion of the door and car body lying to the right of the respective parts to which they are connected and 10 the terminal portions of the arms are slotted as at 26 to receive hasps 27 secured to the car door and body whereby preferred types of locks may be applied thereto to effectively lock the door in closed position.
- 15 What I claim is:
- In a device of the class described, a horizontal track having an upwardly opening guide channel and downwardly directed

guide web, a holder device, rollers pivoted in said holder device in spaced relation and 20 engaging in said guide channel, a guard member attached to said holder between said rollers and with an inturned lower end to engage beneath said guide web, a hanger attached at the upper end to said 25 holder and to said guard member and furcated at the lower end, a bracket adapted to be attached to a door and including a lateral extension longitudinally slotted, said extension being movable in the furcated portion of the bracket, and a pin extending through the terminals of the hanger and the slot of the bracket.

In testimony whereof, I affix my signature hereto.

JOHN A. GIBSON.
